Primary Examiner — Lilyana Bekic(74) *Attorney, Agent, or Firm* — Jonathan Anderson(57) **CLAIM**

We claim the ornamental design for a secured medication transfer set, as shown and described.

DESCRIPTION

FIG. 1 is a perspective view of a first embodiment for a secured medication transfer set showing our new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 with another embodiment of the adapter being claimed view of a second embodiment for a secured medication transfer set showing our new design; FIG. 9 is a front elevational view thereof; FIG. 10 is a rear elevational view thereof; FIG. 11 is a left side elevational view thereof; FIG. 12 is a right side elevational view thereof; FIG. 13 is a top plan view thereof; and, FIG. 14 is a bottom plan view thereof. The broken lines in the drawings depict portions of the secured medication transfer set that form no part of the claimed design.
